[57] CLAIM

The ornamental design for a fin, as shown and described.

DESCRIPTION

FIG. 1 is a side view of a fin showing my new design;
FIG. 2 is a plan view;

FIG. 3 is a underside view;

FIG. 4 is an elevated side view;

FIG. 5 is an elevated front view;

FIG. 6 is a second underside view;

FIG. 7 is a plan view of a second embodiment of a fin showing my new design;

FIG. 8 is a partial front view of FIG. 7, the bottom portion of the blade being omitted for ease of illustration;

FIG. 9 is a plan view of a third embodiment of a fin showing my new design; and,

FIG. 10 is a partial front view of FIG. 9, the bottom portion of the blade being omitted for ease of illustration. The undisclosed side views of the second and third embodiments being the same as the first embodiment.
